UNITED STATES PATENT OFFICE.

ROLLIN H. WHITE, OF CLEVELAND HEIGHTS, OHIO, ASSIGNOR TO THE CLEVELAND TRACTOR COMPANY, OF EUCLID, OHIO, A CORPORATION OF OHIO.

TRACK-LAYING TRACTOR.

1,275,344.

Specification of Letters Patent. Patented Aug. 13, 1918.

Application filed January 28, 1918. Serial No. 214,189.

To all whom it may concern:

Be it known that I, ROLLIN H. WHITE, a citizen of the United States, residing at Cleveland Heights, in the county of Cuyahoga and State of Ohio, have invented a certain new and useful Improvement in Track-Laying Tractors, of which the following is a full, clear, and exact description.

This invention is an improvement upon 0 track laying tractors of the type disclosed in my prior Patent No. 1,253,319.

Tractors of this sort are generally used in the open, and through sand, soft loam, dust and mud. The problem of keeping 15 the working parts of the machinery properly lubricated and free of dirt, dust and mud has been a serious one for the constructors of tractors of this general type. The present invention is believed to be a 20 satisfactory solution of this problem, so far as concerns the driving sprocket and the driving mechanism therefor.

The invention consists in the construction and combination of parts shown in the 25 drawing and hereinafter described and definitely pointed out in the appended claims.

In the drawings, Figure 1 is a side elevation of a tractor in which the invention is 30 embodied; Fig. 2 is a diametrical vertical section through the upper two-thirds (about) of one driving sprocket, and shows also some adjacent parts; Fig. 3 is a vertical section on line 3—3 of Fig. 2; Fig. 4 is 35 a sectional view in the plane indicated by line 4—4 on Fig. 2, and Fig. 5 is a sectional view looking upward of a small segment of the top part of the sprocket, the section being in the plane of line 5—5 on 40 Fig. 2.

The tractor shown in the drawing is substantially like that which is shown in the above mentioned prior patent in many respects. It includes a main frame 10 for 45 supporting the motor and much of the power transmitting mechanism. A nonrotating axle 14 is fixed to and projects laterally from each side of the main frame.

On each side of the main frame and hung 50 upon the projecting end of the axle is a traction frame represented as an entirety by 20. Interposed between the front ends of these traction frames and the main frame is a spring 16 by which the front end of 55 the main frame is supported. Each trac-

tion frame consists of two parallel built up beams 21, 22, which are connected together at their front end by a yoke 23, and are likewise connected between their ends by several cross bars 20^a. Two journal boxes 60 24 and 25 are associated with each traction frame, and are rotatably mounted upon the projecting end of the nonrotating axle 14. These two journal boxes are respectively fixed to the tops of angle irons 21^a and 22^a 65 which respectively form the top members of the two built up beams 21, 22, which are parts of each traction frame.

A casing 30 is fixed to the main frame for housing the differential mechanism (not shown). An alined laterally extended driving shaft 33 extends through the housing on each side of the machine, and projects out of the housing, and has a pinion 32 fixed to 70 its outer end.

A driving sprocket 40 is rotatably mounted upon the axle 14 between the two built up side beams 21, 22, of each traction frame, and this sprocket carries an internal ring gear 41 with which the associated pinion 32 80 85 engages, whereby the sprocket may be rotated. An idler wheel 42 is rotatively mounted in the front end of each traction frame, between the two side beams thereof; and the linked track belt 15 runs over the sprocket 40 and idler 42.

The above mentioned parts are generically like the corresponding parts shown and described in said prior patent; but in the construction shown in said prior application there are no means provided for preventing the dirt, mud, dust, etc., from getting into the sprocket wheel and lodging upon the ring gear or the driving pinion therefor, and there is no adequate means 90 95 for keeping the bearings of said sprocket free from dirt or dust. The present invention relates to the means for accomplishing this desirable result.

Each sprocket wheel is formed as shown, 100 of a casting having as integral parts an outside annular disk 40^a and integral concentric hub 40^b which projects inward from said disk, and an annular cylindrical flange 40^c which also projects inward at the outer 105 margin of the disk. The sprocket teeth 40^a are on the outer periphery of said flange 40^c. The hub 40^b is as stated rotatably mounted upon the axle 14 with roller bearings of familiar form interposed between the axle 110

and hub. The ring gear 41, is fitted into and secured within the cylindrical flange 40^c.

An annular disk 50 is employed as the inner wall of that chamber 44 within the sprocket wheel 40, which results from the described construction thereof. This disk 50 is secured by bolts to the outer end of the housing 30. The outer margin of the disk is of conical form which is complementary to the conical inner periphery 40^c of the flange 40^c at the inner edge thereof. These conical surfaces need not fit each other nicely but should be close to one another to prevent any large particles of dirt from getting to the oil and dust proof joint now to be described.

This disk has a centrally disposed hole around which is a cylindrical flange 51 that nicely fits upon a cylindrical boss 25^a formed on the outside end of the inner journal box 25. Therefore when the traction frame 20 oscillates upon the axle 14 and the journal box moves with said traction frame, the journal box will continue to make a substantially dust and oil tight joint with plate 50 which has no movement relatively to the main frame because it is secured to the housing 30.

60 represents an annular cupped felt washer, that is a flat annular washer whose outer margin 60^a is bent into substantially cylindrical form and fitted against the cylindrical inner face of the flange 40^c.

70 represents a spring metal annulus 35 whose outer periphery is bent into substantially cylindrical form, and is notched to thereby form a multitude of spring fingers 70^a which when the spring annulus and felt washer are assembled and connected as 40 shown, will engage the inner periphery of the cylindrical part 60^a of the felt washer, and press it tightly into engagement with flange 40^c and make an oil and dust tight joint. An annular rib 50^b is formed on the 45 outer face of disk 50. The spring annulus 70 is placed against this; the felt washer is placed against the annulus 70, and a flat clamping ring is placed against the felt washer, and these three parts are secured by 50 rivets or the like to the face of the rib 50^b. The multitude of springs keep the margin of the felt washer in oil and dust tight contact with the flange 40^c; and they continue to do this until the felt is entirely worn out.

55 A similar cupped felt washer 80 is secured in an annular recess in the outer face of the sprocket adjacent the hub thereof, and the cylindrical part 80^a of this cupped felt washer bears upon a cylindrical boss 24^a 60 formed on the inner face of the journal box 24. A flat spring ring 81 is also clamped in this recess against the felt washer, but its inner portion is bent outward and it is slotted to make a multitude of small spring 65 tongues 81^a, each of which bears upon the

cylindrical part of the felt washer and keeps it pressed against the cylindrical boss 24^a.

It will be understood from the foregoing description that the traction frame may oscillate as required upon axle 14, relatively to both the main frame and sprocket, and that the sprocket may be driven as well when the traction frame is oscillating as when it is not, and that none of these relative movements tend to render the dust and oil tight joints 70 inoperative, and that therefore the hollow sprocket may contain at all times an adequate supply of oil to keep its bearings lubricated, and to keep the intermeshing ring gear and pinion lubricated,—without danger 75 of the entry of dust or mud into said wheel chamber.

Having described my invention, I claim:—

1. In a track laying tractor, the combination of a main frame, a nonrotating axle 85 fixed thereto and extending transversely thereof, a traction frame comprising two connected side beams, a journal box fixed to each of said side beams and rotatably mounted on said axle, a driving sprocket 90 wheel comprising an outside disk and a hub which extends inward therefrom and is rotatably mounted on said axle between said side beams and a concentric cylindrical flange, a disk which is fixed to a part carried 95 by the main frame, means for making an oil and dust tight joint between said flange and disk, the inner journal box referred to having a cylindrical boss on its outer face, and said disk having a cylindrical central 100 opening which nicely fits said cylindrical boss, and the outside journal box having a cylindrical boss on its inner face, means for making an oil and dust proof joint between said sprocket wheel and said last mentioned 105 cylindrical boss, an internal gear ring fixed within the cylindrical flange of the sprocket wheel, a driving shaft mounted on the main frame and extending through said disk, and a pinion fixed to said driving shaft in mesh 110 with said internal gear.

2. In a track laying tractor, the combination of a main frame, a transversely extended axle carried thereby, a traction frame comprising two connected side beams, a journal 115 box mounted on said axle and fixed to the outer side beam of the traction frame, and having a cylindrical boss on its inner face, a journal box mounted on said axle and fixed to the inner side beam of the traction frame 120 and having a concentric cylindrical boss on its outside face, a driving sprocket comprising (1) a hub which is rotatably mounted on said axle between said journal boxes, (2) a concentric cylindrical flange, and (3) 125 a disk which connects and closes the space between the outer end of the hub and the outer edge of said flange, there being an oil tight joint between said sprocket wheel and the cylindrical boss on the outside 130

journal box, a shaft housing fixed to the main frame, a driving shaft mounted in and projecting from said housing, a pinion on the projecting end of said shaft, an internal gear ring fixed within the flange of the sprocket wheel in mesh with said pinion, and an annular disk which is rotatably mounted on the cylindrical boss of the inner journal box and is fixed to the outer end 10 of said housing and is fitted within and has a dust and oil tight joint with the cylindrical flange of the sprocket.

3. In a track laying tractor, the combination with a main frame, a transversely extended axle fixed thereto, a shaft housing fixed to said main frame, a driving shaft mounted within and projecting from said housing, a pinion fixed to the projecting end of said shaft, a driving sprocket comprising 20 a hub which is rotatably mounted on said axle, a concentric cylindrical flange, and a disk which connects and closes the space between the outer end of said hub and the outer edge of said flange, an internal gear ring fixed within said flange in engagement with said pinion, an annular disk which is fixed to the end of said shaft housing and is fitted within and has an oil and dust proof joint within the cylindrical flange of said sprocket.

30 4. In a track laying tractor, the combination with the main frame, a transversely extended axle fixed thereto, a shaft housing fixed to said main frame, a driving shaft mounted within and projecting from said housing, a pinion fixed to the projecting end of said shaft, a driving sprocket comprising 35 a hub which is rotatably mounted on said axle, a concentric cylindrical flange, and a disk which connects and closes the space between the outer end of said hub and the outer edge of said flange, an internal gear ring fixed within said flange in engagement with said pinion, an annular disk which is fixed to the end of said shaft housing and 40 is within a cylindrical flange of said sprocket, a cupped felt washer fixed to said disk and formed with a substantially cylindrical outer portion which fits within said cylindrical flange, and a plurality of independently acting 45 springs exerting outward pressure against the cylindrical part of said felt washer.

50 5. In a track laying tractor, the combina-

tion with the main frame, a transversely extended axle fixed thereto, a shaft housing 55 fixed to said main frame, a driving shaft mounted within and projecting from said housing, a pinion fixed to the projecting end of said shaft, a driving sprocket comprising a hub which is rotatably mounted on said axle, a concentric cylindrical flange, and a disk which connects and closes the space 60 between the outer end of said hub and the outer edge of said flange, an internal gear ring fixed within said flange in engagement with said pinion, an annular disk which is 65 fixed to the end of said shaft housing and is fitted within the cylindrical flange of said sprocket, a cupped felt washer fixed to said disk and having its cylindrical portion fitted 70 into the cylindrical flange of said sprocket wheel, an annular disk of spring metal fixed to said disk having its outer edge bent into substantially cylindrical form and notched to form a multitude of outwardly 75 pressing springs which engage the cylindrical portion of said felt washer and yieldingly press it into engagement with the cylindrical flange.

6. In a track laying tractor, the combination with the main frame, a transversely extended axle fixed thereto, a shaft housing fixed to said main frame, a driving shaft mounted within and projecting from said housing, a pinion fixed to the projecting end 80 of said shaft, a driving sprocket comprising a hub which is rotatably mounted on said axle, a concentric cylindrical flange, and a disk which connects and closes the space between the outer end of said hub and the outer edge of said flange, an internal gear ring fixed within said flange in engagement 85 with said pinion, an annular disk which is fixed to the end of said shaft housing and arranged within said cylindrical flange, a felt washer fixed to one of the last mentioned parts and engaging the other, and a plurality of springs fixed to the same part to which the felt washer is fixed and acting upon the washer to yieldingly press it into 90 engagement with the part with which it engages.

In testimony whereof, I hereunto affix my signature.

ROLLIN H. WHITE.
